UNITED STATES PATENT OFFICE.

JAMES W. PACKARD, OF WARREN, OHIO.

ELECTRIC TRANSFORMER.

SPECIFICATION forming part of Letters Patent No. 639,276, dated December 19, 1899.

Application filed January 19, 1899. Serial No. 702,698. (No model.)

To all whom it may concern:

Be it known that I, JAMES W. PACKARD, a citizen of the United States, residing at Warren, in the county of Trumbull and State of Ohio, have invented certain new and useful Improvements in Electric Transformers, of which the following is a specification.

My invention relates to improvements in the cores of transformers and to various details of construction and arrangement, all of which will be fully described hereinafter in connection with the accompanying drawings, in which—

Figure 1 is a rear view of the transformer, part of the casing being broken away to show the interior construction. Fig. 2 is an end view of the transformer. Fig. 3 is a plan view of the same with cover removed. Fig. 4 is a vertical section on the line 4 4 of Fig. 3, the winding being shown in full. Fig. 5 is a perspective view of one form of my improved core. Fig. 6 is a view of two of the strips or laminæ of which the core is composed. Fig. 7 is a perspective view of one end of a core-section. Fig. 8 is a plan view of an assembling-box; Fig. 9 is a perspective view of another form of core embodying my invention. Fig. 10 is a plan view of core-section shown in Fig. 9, with winding added. Fig. 11 is a perspective view of the end of one of the core-sections illustrated in Fig. 9. Figs. 12 and 13 are perspective views of the side and end sections of a core, respectively, showing a modification.

Referring to Figs. 1 to 4, inclusive, A indicates the casing of the transformer, and a a top or cover of the casing. The casing is provided on its back with two pairs of hooks 1, into which fit cross-bars 2 of a frame, upon which the transformer may be hung when it is desired to support it upon a pole. To the ends of the bars 2 are attached vertical bars 3, which have rectangular hooks 4 at their upper ends adapted to fit over a cross-arm 45 upon a pole.

At each end of the casing, near the top, is a depending hook, under which a rope may be passed for the purpose of hoisting the transformer. The hooks 5 are on projecting brackets 6, which are used as supports for the bolts 7, by means of which the covers are fastened.

The bolts pass through holes in the covers and corresponding holes in the brackets 6.

The transformer-core B is a rectangular structure composed of strips or laminæ, which 55 are interlocked, as will be hereinafter explained. The strips forming the core are securely held together by metal clamps 8, which are insulated from the core by strips 9 of suitable material. The clamps 8 of the core rest 60 upon the bottom of the casing, and the core is centered and held from lateral movement by projections 10, extending upward from the bottom of the casing at its sides and ends. After the transformer is set into the casing 65 a pair of stout bars 11 are placed across the top of the casing a short distance above the transformer-core, the ends of the bars being held in recesses beneath shoulders 12, which are cast on the inner face of the casing. 70 Tapped into the middle of each of the bars 11 is a set-screw 13, the lower end of which is arranged to bear upon the clamps 8 at the top of the core. The clamping-screws 13 therefore hold both the bars 11 and the transformer 75 tightly in their respective positions in the casing, the bars being pressed upward and the transformer downward.

The wall 14 of the casing extends upward part way to the cover. Outside of the upper 80 portion of this wall, at the corners of the casing, are compartments 15, which have outer walls 16, fitting the cover. In the bottoms of these compartments 15 are the insulating-bushings 17, through which the wires enter 85 and leave the transformer. Fastened to the inside wall of the casing is a porcelain connection-board 18 for connecting the primary coils in series or multiple.

Figs. 5, 6, and 7 illustrate the construction 90 of a simple form of core embodying my invention. The sides and ends of the core are formed of strips of thin iron, cut as shown in Fig. 6. All of the strips are cut square at one end and inclined at the other, the inclined end preferably making an angle of forty-five degrees with the longer side of the strip. The pieces for the sides are all exactly alike, and the pieces for the ends are exactly alike also, but preferably shorter than the side pieces.

In Figs. 12 and 13 a simple modification of

the invention is illustrated. A side section of the core is shown in Fig. 12, composed of rectangular strips 43 and strips 44, which are inclined at both ends, the bundles of strips 43 being arranged alternately with the bundles of strips 44. All of the strips in this side section are of the same length and arranged to register at their back edges 45, thus forming solid ends, which are adapted to be held in a chuck. The end section illustrated in Fig. 13 is composed of bundles of strips 46, which are inclined at both ends and adapted to fit against the inclined ends of the strips 44. Between the bundles of strips 46 are alternate bundles of short rectangular strips 47, which fit against the ends of the rectangular strips 43.

The manner of assembling the strips to form the sides may be explained with reference to Fig. 7. The strips are assembled in bundles, each containing a given number—say two, three, or four. The bundles are then assembled, with the inclined ends arranged alternately with the square ends. Thus the alternate bundles are arranged with their inclined ends 19 at the top, and the adjacent bundles are arranged with their square ends 20 at the top and their inclined ends at the bottom. All the strips constituting the side sections of the core are exactly of the same length, and when assembled their extreme ends are made to register, forming a straight line 22 along the outer edge. The end of the section adjacent to the line 22 is solid and adapted to be clamped and held in a chuck without injury.

The core-section construction above described has a number of advantages. The plates can all be formed by shearing, which is very much cheaper than punching the plates with dies. It will be obvious that the laminæ may be formed by shearing sheet-metal plates into strips and then shearing the strips on alternate square and diagonal lines. It is not essential that the angle of the inclined end should be forty-five degrees. It may be more for the sides and less for the ends, or vice versa, the sum of the two angles being ninety degrees. It is most convenient and economical, however, to shear on an angle of forty-five degrees, as shown in Figs. 6 and 7.

Another advantage of my improved core is that the mortises only extend half way through the ends of the side sections, leaving the remainder or back portion of each end solid and adapted to be grasped by a chuck without danger of bending the plates. On one side the core is solid to the end of the section, as shown along line 22 in Fig. 7. The core can be chucked for winding without putting filling-pieces in the mortises.

Another advantage of my core construction is found in the ease with which the strips for the side sections can be assembled. I assemble them in a box D, comprising a base 23 and box-like projections 24. The box ends

24 are of such size and are arranged so that the square ends of the plates fit in them exactly when the plates are laid on the base 23. In assembling a core-section the workman simply places the strips in the box D, being careful to get the same number of strips in each bundle and to arrange the successive bundles with the inclined ends alternately at opposite ends of the box. The strips may be compressed and fastened together by a wrapping of heavy paper in the usual manner before they are removed from the assembling box.

My invention is applicable to cores having other forms of cross-section. Thus in Figs. 9, 10, and 11 I have illustrated it as applied in the construction of a core the side sections of which have a star-shaped cross-section, as illustrated in Fig. 10. This star-shaped cross-section is better adapted for winding than the rectangular cross-section of the core illustrated in Figs. 5 and 7. By assembling the strips properly the eight projecting corners of the star-shaped section can be brought into a circle, as illustrated in Fig. 10, which shows a coil in diagram.

Referring to Figs. 9, 10, and 11, it will be seen that the side sections of the core are constructed of a number of groups of wide plates 25, cut and arranged exactly as those shown in Fig. 7, and a series of groups of narrow plates 26, arranged on each side of the wide plates. The narrow plates are preferably of the same length as the wide plates, and their inclined ends are preferably cut away at a less angle than forty-five degrees, so that the plates in the end sections may be all of the same width, as shown in Fig. 9. The middle plates of the end sections have their angular ends cut on an angle that is a complement of the angle of the side plates 25, and the outer plates of the end sections also have their angular ends cut on an angle that is the complement of the angle of the side plates 26.

The end section of the core shown in Fig. 5 is formed by stacking the successive groups of strips with their inclined ends turned in opposite directions, the inclined end of each group projecting beyond the square ends of the adjacent groups. Instead of stacking the plates for the ends before assembling the core the side sections of the core may be set up and the groups of end plates inserted, three or four at a time, in their proper positions between the side sections, the square ends fitting against the square ends of the side sections and the inclined ends fitting in the recesses between the square ends of the side sections and abutting against the inclined ends of said side sections. The end sections of the form shown in Fig. 9 are constructed in substantially the same manner.

Having described my invention, what I claim, and desire to secure by Letters Patent of the United States, is—

1. In a converter-core, the side sections

composed of groups of strips of equal length, the groups being arranged side by side and having square and inclined ends alternating, and the extreme ends of all of the strips being arranged to register, whereby the sections are provided with solid ends adapted to be held in a chuck for winding, substantially as described.

2. In a converter - core, the side sections composed of groups of strips of equal length which are square at one end and inclined at the other, the groups being arranged side by side with the square and inclined ends alternating, and the extreme ends of all of the strips being arranged to register, whereby the sections are provided with solid ends adapted to be held in a chuck for winding, substantially as described.

3. A converter - core having its sides and ends built up of groups of strips each having a square end and an inclined end, the said groups being arranged with the inclined ends alternately facing in opposite directions, the ends of all the strips in the side sections being arranged to register, and the inclined ends of the strips in the end sections being arranged

to break joints with the adjacent square ends of said end sections and to fit between the square ends of the side sections, substantially as described.

4. In a converter, the combination with the casing and the core, of the projections upon the bottom of the casing for holding the lower end of the core, shoulders at the upper end of the casing, transverse bars inserted under the shoulders and above the core, and set-screws extending through said bars and bearing upon the upper end of the core, substantially as described.

5. In a converter, the combination with the casing and two pairs of depending hooks upon the back thereof, of the frame comprising horizontal bars for engaging said hooks and vertical bars attached to the horizontal bars and provided with hooks at their ends, substantially as described.

In testimony whereof I affix my signature in presence of two witnesses.

JAMES W. PACKARD.
